MEANS FOR TREATING MULTIWOVEN FABRICS

Edwin J. Gibbons, East Providence, R. I.

Application April 14, 1942, Serial No. 438,867

6 Claims. (Cl. 139—35)

This invention relates to means for treating multi-woven fabrics, and more particularly to a mechanism for cutting the cross over threads connecting the top and bottom continuous webs of a fabric structure of this character in the process of its formation on a loom and in synchronism with the weaving operation.

In the formation of multi-woven fabric structures, such as ladder tapes and the like, the fabric assembly is formed with oppositely positioned top and bottom body bands or continuous webs, having intermediate tapes located therebetween, the warp threads of which are interwoven with the top and bottom body webs alternately and in a transversely offset relation with each other throughout the longitudinal extent of the formed fabric.

The top and bottom body webs are positioned in the loom one directly above the other, and are each formed of warp and weft threads woven independently of the other body web at all times. The intermediate tapes may each be formed from its own warp and weft threads, or may comprise separate warp threads only, and although the intermediate tapes may be positioned obliquely relative to each other during the operation of weaving, they lie in substantially the same horizontal plane between the top and bottom body webs and in slightly separated transverse relation after being woven.

In the formation of this material the interweaving of the intermediate tapes with the oppositely positioned continuous webs or body bands results in the location of unwoven warp threads at the transition points of the intermediate tapes from one to the other of the opposed continuous bands or webs between the areas of connection of the intermediate tapes with the opposed top and bottom body webs of the fabric. These warp threads are bound into or interlaced with the fabric of the oppositely positioned continuous webs or body bands during the formation of the material, both previously to and subsequently of the transition of said weft threads from one of the continuous body bands to the other, and thus serve to hold the oppositely positioned continuous body bands closely together until these cross over threads are cut to permit displacement of the continuous body bands outwardly from each other, leaving cross straps, formed from the intermediate tape portions, which connect the opposed continuous webs adjacent to their opposite lateral edges to form a ladder-like structure.

At predetermined distances, usually approxi-

mating the width of a slat for which the tape is designed, the warp threads of the intermediate tapes are interlaced with, stitched to or bound into first one, and then the other outer web, the bound areas of each tape to one or the other of the continuous webs being substantially equally spaced from each other, and located in alternate relation with and transversely offset from corresponding bound areas of the other intermediate tape with the corresponding web. Each group of warp threads in one of the intermediate tapes may be described as continually going through the cycle of being bound into one of the continuous webs, then crossing over to the other continuous web, to form a cross strap during which it may be woven or not as desired, then a binding into the other web, and finally a short and immediate cross over to the first continuous web. The short cross over point of each intermediate tape is usually located substantially centrally of adjacent short cross over points of the other tape.

Ventilated hat binding, or helmet tape, is formed in substantially the same manner as Venetian blind tape, the principal difference being that there is usually only a single, centrally located, intermediate tape formed in ventilated hat binding, and the length of the intermediate tape is much shorter than in the case of Venetian blind tape.

Heretofore, after the formation of a narrow fabric structure of the character described the warp threads at the transition points, or cross over threads interconnecting opposite webs, must be cut before the tape can be completed and made ready for use. In general, the cutting of these threads is accomplished by hand. Operatives insert scissors between the oppositely positioned outer webs and sever the cross over thread between each of the points where they are stitched to or interwoven with the oppositely positioned outer webs in the formation of the alternately arranged intermediate tapes. The cutting of these threads is a slow and tedious operation, requiring considerable care and necessitating a great amount of manual labor.

One object of the present invention is the provision of means operated by and in conjunction with the loom mechanism for severing these cross over threads after the completion of the weaving operation and prior to the discharge of the woven fabric from the loom.

Another object of the invention is the provision of means of this character comprising cutting mechanism displaceable transversely of the formed fabric structure and means for actuating

the cutting mechanism in synchronism with the operation of the loom.

A further object of the invention is the provision in a device of this character of means for displacing the cutting means transversely of the formed fabric at each alternate transition of the cross over threads, and means for operating the cutting mechanism at a desired point in the displacement of the cutting means for severing the cross over threads.

Another object of the invention is the provision in a jack operated loom structure of the character described, of cutting means movable to sever cross over threads formed in a fabric material, and jack operated means for actuating said cutting means.

Another object of the invention is the provision of cutting mechanism and a support therefor mounted for reciprocating movement transversely of the paths of travel of fabric structures from the loom, together with means for reciprocating the cutter support in synchronism with the movement of the alternately positioned cross over threads, as the formed fabric moves outwardly from the point of its formation on the loom.

A further object of the invention is the provision of means mounted in operative relation with a loom for severing the cross over threads of plural narrow fabric structures immediately following their formation on the loom, together with means for actuating the cross over thread severing mechanism in timed relation with the rate of fabric formation.

Other objects and advantages of the invention relate to various improved details of construction and novel arrangement of the parts, as will be more fully set forth in the detailed description to follow.

Referring to the drawings:

Fig. 1 is a perspective view of a portion of a multiwoven fabric structure or ladder tape of the character described, showing the location of intermediate tapes, or groups of warp threads serving as intermediate tapes, together with their points of interwoven connection with the continuous outer webs as well as the positions of the cross over threads at the transition points.

Fig. 2 is an edge view of a fabric structure of the character shown in Fig. 1, with the continuous outer webs partially separated from each other adjacent to one end of the fabric material by cutting certain of the cross over threads.

Fig. 3 is a view similar to Fig. 2, showing the fabric structure after the severance of the cross over threads at all transition points to permit displacement of the continuous outer webs from each other substantially to the limit of the distance permitted by the cross straps.

Fig. 4 is a perspective view of a portion of a loom structure, parts thereof being broken away, showing the breast beam in its relation with take-up and delivery rolls together with an improved cutting mechanism arranged in position for operative engagement with the fabric structures as they come from the loom and one form of jack operated means for actuating the cutting mechanism.

Fig. 5 is a front elevational view of a form of cutting mechanism and cutter supporting means therefor adapted for use in cutting the cross over threads of tapes of the character described together with a diagrammatic representation of operating means therefor which may include levers adapted for actuation by jacks or other suitable loom operating elements.

Figs. 6, 7 and 8 are top plan views of one form of cutting mechanism, showing the cutting mechanism in different operating positions with reference to the tape structure,

5 Fig. 9 is an enlarged sectional view of the cutting mechanism shown in Figs. 6, 7 and 8, taken substantially along the line 9-9 of Fig. 8.

Fig. 10 is an enlarged sectional view showing means operatively connecting the cutter operating disk and actuating slide, taken substantially along the line 10-10 of Fig. 6.

Fig. 11 is a perspective view of a portion of a loom structure, parts thereof being broken away, showing the breast beam in its relation with the take-up and delivery rolls, together with cutting mechanism arranged in position for operative engagement with narrow fabric structures, coming from the loom together with a modified form of jack operated mechanism for actuating the cutting mechanism,

20 Fig. 12 is a top plan view showing a pair of delivery rolls with a cutter supporting slide operatively positioned relative thereto and provided with a modified form of cutting mechanism for cutting cross over threads, together with a diagrammatic representation of means for actuating the slide from any suitable or desired form of jack operated means which may be a part of the loom mechanism,

30 Fig. 13 is an enlarged top plan view of one form of cutter which may be employed in connection with the mechanism as shown in Fig. 12, and,

Fig. 14 is an enlarged detail sectional view, 35 taken substantially along the line 14-14 of Fig. 13.

In the embodiment of the invention illustrated herein, Figs. 1 to 3, inclusive, show somewhat in detail a conventional form of ladder tape of a type which in its formation has cross over warp threads connecting the oppositely positioned continuous webs.

40 In this form of construction, 1 designates the woven assembly generally, which comprises oppositely positioned outer webs 2 and 3, interconnected by series of intermediate tapes or intermediate groups of warp threads designated by reference characters 5 and 6, and which are spaced inwardly from the lateral edges of the webs to provide marginal areas 7 and 8 located outwardly of the intermediate tapes 5 and 6, respectively.

45 In the formation of the fabric, portions of the intermediate tapes or cross straps 5 are interwoven with the continuous webs 2 and 3 at points indicated by the reference characters 10 and 11, respectively, and between these interwoven areas the warp threads of the tapes cross over from one of the continuous outer webs to the other to form an interwoven area with the other continuous outer web before the main cross strap portion of the tape is formed independently of either of the continuous outer webs. At each transition point of an intermediate tape a plurality of warp threads 12, located between the interwoven areas 10 and 11, connect the webs 2 and 3. These warp threads 12, hereinafter termed cross over threads, connecting the opposed webs 2 and 3, must be severed before the webs 2 and 3 can be separated from each other to render the completed ladder tape ready for use.

50 In a similar manner, the connection of the intermediate tapes 6 with the continuous outer webs 2 and 3 are indicated by reference characters 14 and 15, respectively, and the cross over threads 75

55 14 and 15, respectively, and the cross over threads

connecting the webs 2 and 3 between adjacent interwoven areas are designated by the reference character 16.

It will be noted that in the formation of the structure shown, the intermediate tape series 5 and 6 have their points of interwoven connection with the continuous webs 2 and 3 spaced from each other longitudinally of the webs in such a manner that the cross over threads 12 and 16 are spaced from each other substantially equally throughout the length of the fabric material and are located in alternately arranged transversely offset relation with each other longitudinally of the formed fabric.

A fabric structure comprising continuous webs connected by cross straps or intermediate tapes and having cross over threads formed therein which connect the continuous webs at intervals may be woven on what are commonly termed narrow fabric looms, which in addition to well-known weave forming mechanisms comprise the usual take-up and delivery rolls located adjacent to the forward end of the loom to engage the formed material and exert a continuous drawing action thereon for moving the fabric structures forwardly from the point of weaving to the point of their discharge from the loom.

On Fig. 4 of the drawings is shown one form of thread cutting mechanism associated with a loom structure of a conventional type, such as is adapted for use in weaving narrow fabrics of the character described, and in which certain loom operations as well as the operation of the cutting mechanism is effected by means of jacks acting through cables and certain connecting and directing mechanisms which have been omitted from the showing in the interest of clearness.

In Fig. 4 there is shown a breast beam 18 suitably positioned with relation to the drawing rolls, and with which may be associated any suitable form of weave forming mechanism including a plurality of vertically displaceable harness frames 20 adapted for operation by jacks 21 and 22 located at opposite ends of the loom structure through appropriately directed cables 23 and 24 respectively which may be passed over pulleys 25 and 26 for connection with the harness frame.

Rotatably mounted in suitable position relative to the breast beam 18 is a take-up roll 28 and delivery rolls 27 and 29 adapted to engage the formed fabric and draw it from the loom while maintaining the same under substantially uniform and constant tension during its travel from the loom until discharged from the delivery roll 29. The rolls 27, 28 and 29 are rotatably supported by suitable frame members (not shown), and are rotated by any suitable means operated in timed relation with the weave forming mechanism of the loom, as is common in devices of this character. The rolls 27 and 28 may be of substantially equal size, while the final delivery roll 29 is preferably of somewhat greater diameter than the roll 27 to insure the maintaining of the desired tension on the fabric structures between the rolls 27 and 29 sufficient to hold the material taut, the rolls 27 and 29 are preferably provided with roughened or tractive surfaces upon those portions which are engaged by the fabric structures to prevent slippage of the fabric relative to the roll surfaces, as indicated at 30 and 31 respectively.

The narrow fabric structures or fabric strips 1 pass downwardly from the breast beam 18 after their formation beneath the roll 28, then upwardly over the roll 27 and downwardly and for-

wardly over the roll 29 for final discharge from the loom. Mounted upon the front face of the breast beam 18 are brackets 34 (only one of which is shown) pivotally supporting downwardly extending arms 35, of any suitable character, which are each provided at its lower end with a bearing 36 for supporting rotatably a pressure roll or knee roll 37 in position to engage and press against each fabric structure as it passes over the main drawing roll 29. The application of pressure to the narrow fabric strips on passing over the roll 29 results in a definite and substantially uniform frictional engagement between the roughened surfaces 31 of the roll 29 and the fabric material thereby insuring substantial tension on the fabric in its passage from the roll 27 to the roll 29.

The mechanism described above, as shown in Fig. 4 of the drawings, is of a character and type such as is commonly employed in machines of this character and is here shown and described for illustrating the relationship existing between the conventional loom structure and the improved cutting mechanism which is hereinafter more particularly set forth.

25 A plurality of downwardly extending brackets 40 may be secured to the breast beam 18 and extend downwardly therefrom to provide support for the cutter carrying mechanism. Each bracket 40 is provided with parallel openings or guide rests 41 and 42 adapted to receive and support cutter operating and supporting bars 43 and 44 respectively, which extend substantially throughout the effective length of the loom. Each guide rest or opening 41 is of somewhat greater width than the cutter operating bar 43 carried thereby in order to permit movement of the bar 43 toward and from the bar 44 in the operation of the mechanism, while the guide rest 42 is of substantially the same width as the cutter carrying bar 44 to permit longitudinal movement of the bar 44 in a substantially fixed path only. Each cutter carrying bar 44 supports a plurality of cutter units, one for each narrow fabric strip to be formed by and discharged from the loom.

45 In the form of the invention shown in Fig. 4 of the drawings these cutter units each comprise a fixed cutter 46 and a movable cutter 47, together with an operating disk 48 adapted for actuation by the cutter operating bar 43, after 50 a manner hereinafter more fully described, to operate the movable cutter 47 at suitable intervals. One of the cutter units above described is located in operative relation with each narrow fabric structure passing between the rolls 27 and 29, and the several units are displaceable simultaneously by longitudinal movement of the cutter carrying bar 44 to bring the units into operative engagement with the narrow fabric structures substantially simultaneously for severing certain 55 of the correspondingly positioned sets of cross over threads of each structure through a single operation of the cutter operating bar 43.

Operating cables 50 and 51 are connected with the ends of the cutter operating bar 43 and cutter carrying bar 44 which are located at the right, as seen in Fig. 4, and these cables may be passed over fixed pulleys 52 and 53 respectively and actuated from certain of the jack operated cables 54 to move the bars 43 and 44 to the right, as shown in Fig. 4, in timed relation with the operation of the loom mechanism. Similar operating cables 55 and 56 connected to the ends of the bars 43 and 44 at the left hand end of the machine, as seen in Fig. 4, may be passed over fixed pulleys 57 and 58 and operatively connected with

jack cables 59 to provide for displacing the bars 43 and 44 toward the left as seen in Fig. 4, through operation of certain of the jacks 22 in timed relation with the operation of the loom mechanism.

The particular form and construction of the cutting units as shown in Fig. 4 may correspond with that of the cutting units shown in Figs. 5 to 11 in all respects and may be operated in a similar manner for severing the cross over threads, except that the means for effecting longitudinal movement of the cutter operating and cutter carrying bars 43 and 44, differ from each other in certain forms of the invention shown.

As shown in Fig. 5 of the drawings, the cutter carrying bar 44 is positively operated to displace it toward the right (as shown in that figure) to a greater or less degree, dependent upon the position of the cross over threads to be severed, and is permitted to move toward the left (as shown in that figure) under the influence of the coiled spring 60. Movement of the cutter carrying bar 44 toward the right, as above described, may be effected by the simultaneous or selective movement of one or both of a pair of levers 61 and 62, which are connected with the cutter carrying bar 44 by a cable 63 passed over a pulley 64 carried by the bar 44. The levers 61 and 62 may be operated by any convenient arrangement of jacks or suitable forms of jack operated mechanisms, or by other means acting in timed relation with the rate of fabric formation.

In a similar manner, the cutter operating bar 43 is adapted to be moved toward the right, as seen in Fig. 5, by movement of a lever 66 to which it is connected by a cable 67 passed over fixed pulleys 68 and 69, while it is moved toward the left, as seen in that figure, by means of a coiled spring 70, which, like the coiled spring 60, is adapted to be connected to a fixed portion of the machine frame or other stationary element. The lever 66, like the levers 61 and 62, may be operated by one of the loom jacks or any suitable form of jack operated mechanism adapted for the purpose, or by other means through which it may be operated in timed relation with the rate of fabric formation.

The cutter supporting and cutter operating means as shown in Fig. 5, like those previously described, are adapted and intended to provide supporting means for and to operate a plurality of cutter units, one of which units is operatively associated with each narrow fabric structure being formed on the loom, and this mechanism differs from the corresponding means shown in Fig. 4 of the drawings, mainly in that the cutter operating bar 43 and cutter supporting bar 44, as shown in Fig. 5, are positively actuated for displacing them in one direction only, being returned to their initial positions by the action of the constantly effective coiled springs 60 and 70.

The particular construction of the elements making up the cutting units as shown in Fig. 4 as well as those illustrated in Figs. 5 to 11, inclusive, will now be described, it being understood that the construction and arrangement of the parts shown and the specific arrangement and application of the operating elements are to be considered as made for the purpose of description only and is not to be taken in a limiting sense.

The fixed cutter 46 may be secured to the cutter carrying bar 44 in any suitable or desired manner, as by bolts or rivets 72, and is provided with a cutting blade 73 cooperatively positioned

with respect to a cutting blade 74 formed on the movable cutter 47. As shown, the fixed cutter 46 may be additionally secured to the cutter carrying bar 44 at the point of its pivotal connection

- 5 with the movable cutter 47 as by means of a bolt 75, provided with a shouldered portion 76, which bolt may be passed through the cutter 46 and cutter carrying bar 44 so that the shoulder 76 will engage and clamp the cutter 46 firmly
- 10 to the bar 44, while a spacing sleeve 77 is mounted on the bolt 75 to provide a bearing for the rotatable disk 48. A nut 78 carried by the reduced portion 79 of the bolt 75 engages the spacing sleeve 77 and serves to draw the cutter 46 into
- 15 firm clamping relation with the bar 44. The cutter 47 may be pivotally mounted upon a reduced portion 80 of the bolt 75 extending upwardly from the shoulder 76, and the threaded end portion 81 of the reduced portion 80 is provided with a shoulder 82 engageable by a nut 83 to secure the movable cutter 47 in position relative to the fixed cutter 46 while permitting movement of the cutter 47 relative to the cutter 46.
- 25 The cutter operating disc 48 is capable of being rotated freely relative to the cutter supporting bar 44 upon the spacing sleeve 77 carried by the bolt 75 and may be connected to the cutter operating bar 43 by a bolt 85 mounted to rotate
- 30 freely in the operating bar 43, as shown in Fig. 10 of the drawings. The bolt 85 has a reduced end portion 86 passed through a sleeve 87 carried by the disc 48 and is provided with a nut 88 by which it may be clamped firmly to the cutter operating disc, as is shown more particularly in
- 35 Fig. 10 of the drawings.

The disc 48 may be provided with an arcuate slot 90 providing means for adjustably connecting the movable cutter 47 thereto by any suitable means, such as is shown in Fig. 10 of the drawings. This connecting means may comprise a bolt 91 having a disc engaging head 92, a disc engaging clamping and spacing sleeve 93 having a portion passed through the movable cutter 47, and a nut 94 for holding the parts in clamping engagement with the disc 48 while permitting movement of the cutter 47 relative to its bearing on the spacing sleeve carrying member 93.

- 50 As shown in Fig. 9 of the drawings, the cutting blade portion 73 of the stationary cutter 46 is recessed upon the face thereof nearest the cutter carrying bar 44, as indicated at 95, to provide a space sufficient to receive the lower web
- 55 of the fabric material as the cutter members are advanced into position to sever the cross over threads 5 and 6, and the ends of the cutter blades 73 and 74 may be inclined somewhat, as indicated at 96, to permit their entry between
- 60 opposed webs 2 and 3 without catching in the fabric material.

In the operation of the cutting mechanism shown in Figs. 4 to 11, inclusive, the narrow fabric structures 1 each pass downwardly from the breast beam 18 beneath the take-up roll 28 and then upwardly over the delivery roll 27 and from there downwardly over the delivery roll 29 and under the knee roll 37 for delivery from the loom. In their passage from the roll 27 to the roll 29, the fabric structures pass, while under substantially uniform tension, over the cutter supporting bar 44. Since the formation of corresponding parts of each narrow fabric strip occurs simultaneously in the loom operation, corresponding cross over threads 12 and 16 present

in the several fabric structures are maintained constantly in substantially a straight line position parallel with the cutter carrying bar 44 during the passage of the fabric strips from the roll 27 to the roll 29.

From this it follows that movement of the cutter carrying bar 44 to bring a cutting unit into position to sever either the cross over threads 12 or 16 of one strip will bring each of the remaining cutter units into position to sever corresponding cross over threads of each of the other fabric strips. When cross over threads, as 12, of the several fabric strips reach a position opposite to the cutter units, the cutter carrying bar 44 is moved to the left by suitable actuating means, as of a character shown in Figs. 4 or 5 of the drawings, to bring the cutting blades into cutting position with the threads, substantially as shown in Fig. 6 of the drawings. The operating bar 43 is then actuated by appropriate means, as of the character shown in Figs. 4 and 5, to move the bar 43 to the right as shown in the drawings. This rotates all of the discs 48 to the right and moves the movable cutters 47 to cut the threads 12. After cutting the threads 12 the cutter operating bar 43 is moved in the opposite direction to rotate the discs 48 and open the cutting blades.

The cutter carrying bar 44 may be moved to the right into its initial position after cutting the cross over threads 12, or may remain partially inserted between the webs until the cross over threads 16 come into position for cutting. In either case, as the cross over threads 16 reach a point opposite the cutter units the cutter carrying bar 44 is displaced longitudinally toward the left as shown in the drawings to bring the cutting blades 73 and 74 into position relative to the cross over threads 16, as is shown in Fig. 7 of the drawings. The cutter operating bar 43 is then again displaced toward the right to close the cutting blades 73 and 74 and sever the cross over threads 16. Immediately following this operation the cutter operating bar 43 is moved to the left to open the cutter blades 73 and 74 and the cutting carrying bar 44 is moved toward the right to bring all cutting units back into their initial position, substantially as shown in Fig. 8 of the drawings. It will be understood that in the form of the invention shown in Fig. 4 of the drawings, the cutter operating bar 43 may participate in the initial movement of the cutter carrying bar 44 toward the left as shown in the drawings, and then be displaced toward the right by force exerted through the cable 50, or may participate only partially in the initial movement of the cutter carrying bar 44 toward the left, being held in its initial position or displaced slightly toward the right, as may be necessary to insure the appropriate movement of the cutting blades 73 and 74 for severing the cross over threads.

The means employed for moving the cutter carrying bar 44 and the cutter operating bar 43, as above described, may be means corresponding with those shown and described in connection with Figs. 4 and 5 of the drawings, or such other appropriate correspondingly acting means as may be found desirable which are capable of actuation in timed relation with the rate of fabric formation of the loom or with the rate of travel of the fabric strips in their passage over the rolls 27 and 29.

In the embodiment of the invention shown in Fig. 11 of the drawings, the mechanism is illustrated in its application to another form of loom

structure in common use which comprises such basic loom elements previously described as the breast beam 18, rolls 27, 28 and 29, and harness frames 20 which are controlled by the weave mechanism. In this, as in the forms previously shown and described, brackets 34 secured to the breast beam have arms 35 depending therefrom to support knee rolls 37 in pressure engaging relation with the fabric strips 1 as they pass over the delivery roll 29. As in the form of the invention shown in Fig. 4 of the drawings, brackets 40 extend downwardly from the breast beam 18 provided with guide rests 41 and 42 for supporting the cutter operating bar 43 and cutter supporting bar 44 respectively, and the cutter carrying bar 44 is provided with a plurality of cutter units, one for each fabric strip 1, which may each comprise a stationary cutter 46, movable cutter 47 and operating disc 48, which may be similar in all respects to those more particularly shown in Figs. 6 to 8 of the drawings as previously described.

In this form of the invention plural jack levers having oppositely directed operating arms 95-96, 97-98, 99-100 and 101-102 are mounted upon a jack shaft 103 and suitable actuating means (not shown) are provided for operating the same in accordance with a predetermined plan of loom operation as is well-known to those skilled in the art. In the form of the construction shown herein the arms 95-96 are connected to opposite sides of a harness frame 20 by cables 104 and 105 passed over fixed pulleys 106 and 107, respectively. Arms 97-98 are connected by cables 108 and 109 with one end of the cutter operating bar 43 and a fixed tension spring 110, respectively. The cable 108 passes over fixed pulleys 111 to its point of connection with the right hand end of the cutter operating bar 43.

The arms 98 and 101 are connected to opposite ends of a cable 114 passed over a movable pulley 115 carried by a cable 116 secured to the left hand end of the cutter carrying bar 44 which is passed over directional pulleys 117 and 118. The arms 100 and 102, associate related with arms 99 and 101, are connected to opposite ends of a cable 120 passed over a movable roll 121 carried by a cable 122 which passes over a fixed pulley 123 and is connected with the right hand end of the cutter carrying bar 44. In this form of the invention the cutter carrying bar 44 is shown as provided with an offset extension 125 to which is connected a coiled spring 126 secured to the left hand end of the cutter operating bar 43 for returning the cutter operating bar into position to open the cutting blades after each actuation of the blades by movement of the cutter operating bar toward the right as seen in Fig. 11 of the drawings.

In the operation of the mechanism shown in Fig. 11 of the drawings the harness frame or frames 20 are moved by actuation of associated lever arms 95-96 after a manner well-known in the art. The cutter carrying bar 44 is adapted for positive actuation in either direction by joint or separate movements of associated pairs of lever arms 99-100 and 101-102, through the connections above described, that is, in the form shown, the cutter carrying bar 44 may be displaced toward the left by movement of one of the lever arms 99 or 101 into position to cut the cross over threads 12 as previously described, and then further actuated in the same direction by movement of the other said lever arm into

position to cut the cross over threads 16 at the opposite side of the tape. By this means, the lever arm first effective to displace the cutter carrying bar 44 to the left may remain in its new position until after further displacement of the cutter carrying bar 44 by actuation of the second lever arm. After the cutting of cross over threads 12 and 16, the cutter carrying bar may be returned to its initial position by the operation of the lever arms 100 and 102, associated with lever arms 99 and 101, either simultaneously or in sequence, corresponding with or dependent upon the previous manner of operation of the lever arms 99 and 101 in displacing the cutter carrying bar 44 toward the left.

As an alternate mode of operation, the cutter carrying bar 44 may be displaced to the left, as shown in Fig. 11, by simultaneous movement of the lever arms 99 and 101 to bring the cutters into position to sever the cross over threads 16 and 12, and then returned to its initial position by simultaneous operation of the lever arms 100 and 102.

In this form of the invention the cutter operating bar 43 is returned to its initial position by the coiled spring 126 after actuation by movement of the lever arm 97, and this is the case whether the cutter carrying arm 44 is located in position for cutting cross over threads 12, or 16, located adjacent to opposite side edges of the tape, at the time of the actuation of the cutter operating bar 43. In this particular form of the invention the cutter operating bar 43 is operatively connected with the lever arm 97 which may be displaced and returned to its initial position immediately after displacement with each movement of the cutter carrying bar 44 toward the left to bring the cutting mechanism into position for severing cross over threads 12 or 16 of the tape. Since the lever arm 97 moves against the tension of the spring 110 and the cutter operating bar 43 is displaced against the tension of the spring 126 the cutter operating bar 43 tends to assume its initial position with relation to the cutter carrying bar 44 upon each return movement of the actuating lever 97 following the displacement of the cutter operating bar 43 toward the right as shown in Fig. 11 of the drawings.

In the form of the invention shown in Figs. 12, 13 and 14 of the drawings a cutter carrying bar 44 is mounted for endwise sliding movement between delivery rolls 27 and 29 of the character above described and is provided with spaced oppositely positioned cutters 130 and 131 to be located upon opposite sides of each narrow fabric structure 1 passing over the delivery rolls 27 and 29 and across the face of the cutter carrying bar 44. The cutter carrying bar 44 is adapted for alternate reciprocation by any suitable means, which may be of a character similar to or corresponding in operation with certain of those previously described or otherwise, and which for the purpose of illustration, are shown as cables 133 and 134 secured to opposite ends of the cutter carrying bar 44 and passed over guide rolls 135 and 136, respectively, for attachment to any suitable actuating means, such as the jack levers previously described.

The cutters 130 and 131 may be so positioned as to bring the cutter 130 into cutting engagement with the cross over threads 12 as shown when the bar 44 is moved toward the left as shown in Fig. 12, while the cutter 131 is so positioned as to be capable of being brought into cutting engagement with the cross over threads

16 located upon the opposite side of the narrow fabric structure as the bar 44 is moved toward the right as shown in Fig. 12 of the drawings.

In this form of the invention the cutter carrying bar 44 may be moved to the right and the left into thread cutting position by any suitable or desired mechanism, other than the means previously shown and described, since the cross over threads 12 and 16 are substantially uniformly spaced from each other throughout the extent of the narrow fabrics structure and are located adjacent to opposite edges thereof, thereby permitting severance of the threads by a continuous uniformly obtained displacement of the cutter carrying bar 44 in opposite directions of substantially uniform degree effected in timed relation with the movement of the fabric structures from the loom.

The cutter members 130 and 131 may be of any suitable or desired form or construction, and for the purpose of illustration are shown herein as each including a casing 137 which may comprise a base 138 and a cover plate 139 provided with a rounded end having an extension 140 adapted to engage with a recess formed in the end of the base 138. A cutting element, such as a razor blade 141 or the like, may be clamped between adjacent surfaces of the base and cover 138 and 139, and a bolt 142 is provided for drawing the base 138 and cover 139 firmly together in clamping engagement with the cutter 141 and at the same time securing the cutter member firmly in position on the cutter carrying bar 44, with the cutting edge of the cutter member projecting from the casing 137 suitably for engaging and severing the cross over threads with which it may be brought into contact by reciprocation of the cutter carrying bar 44 in conjunction with the continuous forward movement of the narrow fabric structures over the delivery rolls 27 and 29.

In each form of the invention shown and described, the cutter carrying and cutter operating bars are shown as operated from levers or cable connections which are operatively connected with certain of the jack members forming a part of the operating mechanism of the loom, in order that the necessary movements of the cutter carrying bar 44, either with or without the cutter operating bar 43, may be made in timed relation with the operation of the loom mechanism or stitch forming means of the loom.

While this form of operating means for the cutting mechanism has been indicated as well adapted to be employed in a device of this character for correlating the operation of the thread cutting mechanism with the loom operation, it is to be understood that any other suitable form of cutter operating mechanism may be used which is capable of being synchronized with the loom operating mechanism or arranged to operate in timed relation with the stitch forming means or the rate of travel of the delivery rolls so as to actuate the thread cutting mechanism at intervals corresponding with those intervening between the location of successive cross over threads on the several narrow fabric strips as they come into position to be engaged simultaneously by the thread cutting mechanism.

70 What I claim is:

1. The combination in a loom structure having harness actuating mechanism for effecting the weaving of ladder tape, of cutting apparatus for severing the cross over threads of said tape, and means connecting said mechanism and said

apparatus whereby the cutting apparatus is actuated by said harness actuating mechanism.

2. The combination in a loom structure having harness actuating mechanism for effecting the weaving of ladder tape, of cutting apparatus for severing the cross over threads of said tape comprising a cutter supporting member movable into and out of thread cutting position, cutters carried by said member, and means actuated by said harness actuating mechanism for moving the said member to bring the cutters into thread cutting position, and means also actuated by said harness actuating mechanism for effecting relative movement between said cutters to sever said threads.

3. The combination in a loom structure having harness actuating mechanism for effecting the weaving of ladder tape, and means for moving the woven ladder tape, of cutting apparatus for severing the cross over threads of said tape, and means actuated by said harness actuating mechanism for effecting movement of said cutting apparatus in a direction transverse to the movement of said tape into cutting position and thereupon effecting the severing of said threads.

4. The combination in a loom structure having harness actuating mechanism for effecting the weaving of ladder tape, and means for moving the woven ladder tape, of cutting apparatus for severing the cross over threads of said tape, and means actuated by said harness actuating mechanism for effecting movement of said cutting apparatus in a direction transverse to and in timed relation with the movement of said tape to bring

the cutting apparatus into cutting position with respect to the said threads and thereupon severing the said threads.

5. The combination in a loom structure having harness actuating mechanism for effecting the weaving of ladder tape and having rolls for moving said tape, of a cutter supporting member mounted for movement in direction parallel to the axis of said rolls, cutters carried by said member for cutting the cross over threads of said tape, and means connecting said member and said cutters with said harness actuating mechanism for effecting movement of said member to bring the cutters into cutting position with respect to said threads and thereupon actuating said cutters to effect severing of said threads.

6. The combination in a loom structure having harness actuating mechanism for effecting the weaving of ladder tape and rolls for moving said tape, of a cutter supporting member mounted for movement in a direction longitudinally of said rolls, a fixed cutting element and a movable cutting element carried by said member for severing the cross threads of said tape, means connecting said member with said harness actuating mechanism for moving said member to bring the cutting elements into thread cutting position in timed relation with the movement of the tape by the rolls, and means actuated by said harness actuating mechanism for effecting movement of the movable cutting element to sever the threads when the cutting elements are in the thread cutting position.

EDWIN J. GIBBONS.
